Application August 18, 1952, Serial No. 21,078

Term of patent 14 years

(Cl. D34—15)

To all whom it may concern:

Be it known that I, Christy M. Del Mas, a citizen of the United States of America, residing at city, county and State of New York, have invented a new, original, and ornamental Design for a Combined Whistle and Container Closure or Similar Article, of which the following is a specification, reference being had to the accompanying drawing, forming part thereof:

Figure 1 is a front elevational view of a combined whistle and container closure or similar article, showing my new design;

Figure 2 is a side elevational view thereof, and

Figure 3 is a top plan view of the same.

The back and side not shown have substantially the same appearance as the front and side shown in Figs. 1 and 2, respectively.

I claim:

The ornamental design for a combined whistle and container closure or similar article, as shown and described.
